UNITED STATES PATENT OFFICE.

JAMES DUNDAS WHITE, OF LONDON, ENGLAND.

COMPOUND BOAT.

942,687.

Specification of Letters Patent. Patented Dec. 7, 1909.

Application filed March 9, 1909. Serial No. 482,235.

To all whom it may concern:

Be it known that I, JAMES DUNDAS WHITE, a subject of the King of England, and a resident of London, England, have made 5 certain new and useful Improvements in Compound Boats, of which the following is a specification.

My invention relates to compound boats and it consists in the constructions, combinations and arrangements hereinafter described and claimed.

The main object of my invention is to provide a compound boat which shall combine great stability with small displacement, and 15 in which each of the several hulls shall have sufficient freedom to roll, pitch, and adjust its heading, so as to avoid those excessive strains which have hitherto hindered the development of boats of this type.

20 A further object of my invention is to provide means for keeping the individual hulls directed in the line of their progress and to prevent "diving" of said hulls.

Further objects and advantages will appear in the following specification and the 25 novel features of the invention will be particularly pointed out in the appended claims.

My invention is illustrated in the accompanying drawing, in which—

30 Figure 1 is a perspective view showing one embodiment of my invention. Fig. 2 is a longitudinal vertical section fore and aft of the compound boat. Figs. 3 and 4 are modified forms of the hulls, and Fig. 5 is a detail sectional view of the universal joint.

The figures are drawn with a view to showing the character rather than the proportion of the parts; thus, for instance, the 40 deck is not intended to be so relatively high above the water, nor the angle of the propeller shaft so much out of the horizontal, and the hulls are not intended to be so short in proportion to their breadth.

45 In carrying out my invention I provide a horizontal framework constituting part of the deck 1. The framework is preferably triangular in plan, but both it and the deck may be of any shape or construction. This 50 framework is supported at three points by the three vertical pieces 2, 3 and 4, each of which is rigid with it and strongly trussed to it by means of the inclined braces. The lower ends of these three vertical pieces rest 55 upon the three hulls A, B and C respectively, each vertical piece being connected

with the hull below it by the universal joint shown in Fig. 5. These joints are of such a character as to transmit the pressure of the superincumbent weight to a point low down 60 in the hull, and to allow the hull to roll, pitch and adjust its heading through sufficient angles.

The construction of the hulls may be seen from the drawings. They are designed 65 with full lines forward and fine lines aft, on what is commonly called the "cod's head and mackerel's tail" principle. The vertical pieces 2, 3 and 4 pass into their respective hulls through the wells 5, 6 and 7. 70 These are preferably shaped like inverted cone frustums and are bulkheaded off from the rest of the hull space. Except for this well, each hull is preferably a water-tight 75 pontoon. In each hull the connecting joint is on or immediately above the keel and the surrounding well is large enough to allow 80 for oscillatory movements. Each joint is placed low down in its hull so as to make the superincumbent weight act as ballast. Moreover, the joint is well forward of the 85 center of lateral resistance of the hull so as to keep the hull heading in the direction of its progress, but is well aft of the center of buoyancy of the hull, so as to prevent "diving".

The hulls need not all be of the same size, but they are all of the same general character and the arrangement of the connecting joint is the same in them all.

90 The construction of the connecting joint is shown in Fig. 5. The end of each of the vertical pieces 2, 3 and 4, terminates in a sphere 8, which rests in a hemispherical socket 9 in a base 10, which is firmly fixed just above the keel. A collar 11, which encircles the upper part of the sphere 8, is arranged to be bolted to the base 10 in the manner clearly shown in the figure. The collar is of such a size as to allow the sphere 100 sufficient range of oscillatory movement, but to prevent it from drawing away from the base. While I have shown a universal joint of specific construction, it will be understood that any joint permitting a free 105 movement of the stationary supports 2, 3 and 4 in any direction, might be substituted for the form herein shown.

110 In each hull the well may be made watertight or approximately so, by covering it with a flexible covering of water-proof canvas or other material attached around its

circumference. The central portion of the covering may surround the vertical supporting piece and be attached to it, and if the covering is loose there will be a sufficient range of movement, while the covering effectually keeps out the water.

For purposes of speed the undersides of the hulls may be either of the ordinary type, as shown in Fig. 2, or they may be 10 constructed on the hydroplane principle as shown in Figs. 3 and 4. In these figures the connecting joint is placed as low as possible in the fore part of the hull.

When the compound boat is to be used as 15 a motor boat, the engine 12 may be placed amidships just abaft the leading hull, the propeller shaft 13 passing between the other two hulls. In Fig. 1 the rudder 14 is shown as placed amidships between the two after 20 hulls, but I do not confine my invention to this or to any other special position or arrangement of the rudder, or to the use of one rudder only.

While I have shown the compound boat 25 as comprising three hulls it will be understood that any number of hulls might be used. So also I do not wish to limit myself to the precise construction in regard to the location of the engine, propeller shaft and 30 rudder shown in Fig. 1, or to the use of a single engine, propeller shaft, propeller, and rudder, since other devices based upon the same general idea might be made without departing from the spirit and scope of this 35 invention.

I claim—

1. In a compound boat, a rigid deck, downwardly extending supports therefor, a plurality of individual hulls, universal joints for connecting each of said supports to one 40 of said hulls said connection being in each case low down in the hull forward of the center of lateral resistance of the hull and abaft of the center of buoyancy thereof.

2. In a compound boat, a rigid deck, downwardly extending supports therefor, a plurality of individual hulls, each provided with a bulkheaded well, universal joints for connecting each of said supports with said hulls arranged in the bottom of said bulkheaded well forward of the center of lateral 50 resistance of the hull and abaft of the center of buoyancy thereof.

3. In a compound boat, a rigid deck, downwardly extending supports therefor, a plurality of individual hulls, each hull being designed with full lines forward and fine lines aft on the "cod's head and mackerel's tail" principle, and having a conical shaped bulkheaded well extending nearly to the 55 keel, universal joints for connecting each of said supports with said hulls arranged in the bottom of said bulkheaded well forward of the center of lateral resistance of the hull and abaft of the center of buoyancy thereof. 60 65

JAMES DUNDAS WHITE.
